TELEPHONE SIGNALING SYSTEM

Albert E. Woodruff, Oak Park, Ill., assignor to
 Associated Electric Laboratories, Inc., Chicago,
 Ill., a corporation of Delaware

Application May 24, 1934, Serial No. 727,226

15 Claims. (Cl. 179—28)

This invention relates to telephone systems but more particularly to improvements in signaling arrangements in such systems. One of the primary objects of the invention is to provide an improved visual and audible signaling means at a subscriber's telephone station. A further object is to simplify the signaling means and equipment at a telephone substation by eliminating the usual ringer coils and gongs and the condenser and 5 instead utilizing the receiver of the substation for an audible signal. A further object resides in providing a neon glow lamp at a telephone substation for controlling the signaling. An additional object consists in an arrangement employing 10 a neon glow lamp which will permit signaling current to pass but will not permit voice currents to pass, thereby eliminating the transmission losses on a party line usually caused when ringers are employed at the substation. A further object 15 is to provide an arrangement for removing the neon glow lamp from the circuit when the receiver is removed and the telephone placed in talking condition. Other objects and features of the invention will appear more fully from the 20 detailed description thereof hereinafter given.

In the arrangements of the invention the neon glow lamp is connected directly across the line conductors in series with the receiver at the substation and is shunted out by the substation 25 transmitter when the receiver is removed. The application of signaling current of audible frequency to the line breaks down the lamp and at the same time actuates the receiver to transmit 30 an audible signal or tone. In order to break down the neon lamp a direct current battery of sufficient voltage is superimposed on the audible frequency current, the direct current being used 35 both as a means of ionizing the neon tube and for polarizing the receiver in case it is of the direct current type without a permanent magnet. After the lamp glows it presents a comparatively 40 low resistance path to the receiver because, due to the characteristics of these lamps, they will stay operated on a lower voltage than that required to break them down.

The invention will be more fully understood from the following description together with the drawing which discloses a preferred embodiment of the invention.

50 Referring to the drawing, there is indicated diagrammatically for the purposes of illustration a manual switchboard having cord circuits such as C. These cord circuits are connected to an operator's telephone by means of answering key AK, while a ringing key RK is for signaling pur-

poses. Each subscriber's line terminates at the switchboard in a line jack J, and has associated with it the line lamp L. A single substation on a line is shown at B while a multi-party line 5 and 6 has a number of substations, A, A' and A² 5 connected to it. The substation A as well as the others is provided with the usual transmitter T, receiver R, and switchhook S. In addition the neon glow lamp N is provided which is normally connected in series with the line conductors 5 10 and 6 and the receiver R, and which is shunted by the transmitter T when the receiver is removed from the switchhook S. A source of low voltage alternating current of any frequency within the audible range, together with a fairly 15 high direct current potential superimposed on the alternating current, is controlled by the signaling key RK in the cord circuit C.

In order to better explain the invention the operations which take place when a call is made 20 will now be pointed out. The subscriber at substation B desiring to establish a connection with a subscriber on the party line 5 and 6, substation A for example, will remove his receiver thereby establishing a direct current circuit path through 25 the transmitter and receiver at substation B, line circuit, contacts of jack J', and through the line lamp L'. The line lamp L' lights and the operator answers by inserting the answering plug P' into jack J' thereby extinguishing the lamp L' at 30 the jack J' contacts. The answering key AK is then operated connecting the operator's telephone directly with the line conductors of substation B. The relay 9 being connected in this circuit operates and closes the circuit for supervisory lamp 35 AL. It also furnishes talking current for the telephones from the battery B—1 through its windings. The operator upon ascertaining the wishes of the subscriber at substation B inserts calling plug P of cord C into jack J, thereby separating the jack contacts 1 and 8 and connecting the cord C directly to the line conductors 5 and 6. 40

The operator now signals the substation A by operating the signaling key RK which thereby connects a source of fairly low voltage alternating current of any desired audible frequency, for example from 300 to 1000 cycles, through the primary and secondary windings of transformer TR, comparatively high voltage direct current battery B—2 superimposed upon the alternating 50 current, contacts of key RK, plug P and jack J, line conductors 5 and 6, and through the neon glow lamp N and the receiver R at substation A. The circuit likewise extends in parallel through all the other substations A' and A². The direct 55

current flowing in the above circuit path ionizes the neon glow lamp N, breaking it down and reducing its resistance so that it remains lighted and provides a low resistance path to the receiver 5 R for the alternating current flowing in this circuit. The direct current in this circuit likewise polarizes the receiver R in case it is of the direct current type not provided with a permanent magnet. The illumination of the neon lamp N will 10 attract the attention of the person at the substation A in case he is some distance from his telephone or in case his hearing is slightly defective. The receiver likewise responds to the frequency of the alternating current to send out an 15 audible howl or tone to attract the subscriber's attention. It will be understood that the neon glow lamp as well as the receiver at the other substations A' and A² on the same line, will respond to the signaling current, and the operator at the 20 switchboard therefore in order to call the substation A only, will manipulate the signaling key RK in accordance with a particular code of long and short periods of signaling.

In answering the call the receiver R is removed 25 from the switchhook S, thereby connecting the transmitter T in series with the receiver R and the line conductors 5 and 6, while at the same time the transmitter T which is of lower resistance shunts the neon glow lamp N from the line 30 circuit thereby extinguishing it and allowing the receiver R to function normally. The operator restores the signaling key RK and then her answering key AK and retires from the connection. The telephone substation B is now in direct 35 communication with substation A and conversation can proceed, current for talking purposes being furnished for both telephones through the windings of relay 9. The supervisory lamp AL therefore remains lighted until both parties have hung up, whereupon the lamp goes out and the operator withdraws the plugs P and P' from 40 jacks J and J' to restore the circuits to normal condition.

It will be observed that when the telephones 45 A and B are in direct communication the receivers at substations A' and A² will not interfere with the transmission or present a loss in transmission usually occurring with the ordinary types of ringing apparatus employed. This is so because the 50 neon glow lamps present an open circuit condition to voice currents on the line and will permit only high potential signaling current to flow through them.

The source of high potential direct current 55 comprising battery B-2 which is superimposed on the alternating current may satisfactorily be substituted for a single direct current battery of sufficient voltage to break down the neon lamp and at the same time maintain it lighted after 60 having operated. In order, however, to actuate the receiver R this direct current source would have to be rapidly interrupted as by a buzzer. Similarly the source of direct current B-2 could be dispensed with and only an alternating current source used to break down the neon lamp and maintain it provided it were of high enough potential, but not to injure the receiver R. It will readily be apparent likewise that neon glow lamps are constructed to break down on different voltages and therefore on the party line illustrated 70 each substation can be provided with a different neon glow lamp while at the switchboard the operator would be provided with different signaling keys each connected to a different potential of 75 battery. In this manner the operator would be

enabled to selectively signal the substations connected to the same line.

It will be appreciated that while the invention has been disclosed only in connection with a manual telephone system it will be equally applicable to an automatic system; and while a simple series telephone circuit has been illustrated the invention may be applied to any other type of substation without departing from the spirit of the invention. It is not desired, therefore, to be limited to the exact disclosure but only to the extent of the appended claims.

What is claimed is:

1. A signaling circuit for a substation telephone comprising a neon lamp connected directly in 15 series with the telephone receiver when the receiver is on the switchhook.

2. A substation telephone line, a signaling circuit bridged across said line at said substation when the receiver is on the switchhook, said signaling circuit including a neon lamp and a receiver connected directly in series therein.

3. A telephone line terminating at a substation, telephone instrumentalities including a receiver at said substation and a switchhook, a signaling circuit normally connected across said line at said substation, before the receiver is removed from the switchhook, including said receiver, and a neon lamp in series with said receiver acting as a normally open valve therefor.

4. In a substation telephone set, a normally closed signaling circuit including a neon lamp and the telephone receiver directly connected in series, and means for shunting said neon lamp from said circuit when the receiver is lifted from 35 the switchhook.

5. In a substation telephone set, a switchhook, a signaling circuit at said set including a neon lamp and the telephone receiver normally connected in series when the receiver is on the switchhook, and means for connecting the transmitter of said set in shunt of said neon lamp to render it inoperative in said signaling circuit and for connecting the transmitter in series with the receiver for talking purposes.

6. In a substation telephone set, a signaling circuit, a neon glow lamp and telephone receiver connected in said signaling circuit, means for transmitting a source of battery potential to said signaling circuit to break down said neon lamp, 50 and means for transmitting a different source of current to said circuit to actuate said telephone receiver as a signal.

7. In a substation telephone set, a signaling circuit, a neon glow lamp and telephone receiver connected to said signaling circuit, means for connecting a source of direct current potential to said signaling circuit to operate said neon lamp as a visible signal, and means for connecting a source of alternating current potential to said signaling 60 circuit to operate said telephone receiver as an audible signal.

8. In a substation telephone set, a signaling circuit including a neon glow lamp and a telephone receiver, a source of direct current and a source of 65 alternating current, means for connecting the source of direct current potential superimposed upon the source of alternating current to said signaling circuit to operate said neon lamp as a visible signal and said receiver as an audible signal.

9. In a substation telephone set, a signaling circuit including a neon glow lamp and a telephone receiver, a source of direct current and a source of 75 alternating current, means for connecting

- 5 said source of direct current potential superimposed upon said source of alternating current to said signaling circuit to operate said neon lamp as a visible signal and said receiver as an audible signal, and a shunting circuit including a telephone transmitter for removing said neon glow lamp from said signaling circuit.
10. In a party line telephone circuit, a line having a plurality of telephones thereon, a signaling circuit for each telephone on the line, a neon glow lamp and a receiver in each circuit, means for operating all the neon lamps and receivers to signal said telephones, means for removing the neon lamp from the signaling circuit of the desired telephone, but maintaining the receiver for talking purposes, the neon lamp of the remaining telephones presenting an open circuit to voice currents and preventing transmission losses.
15. In a multi-party telephone line, a line having a plurality of telephones thereon, a signaling circuit for each telephone on the line, a neon glow lamp and the telephone receiver in each circuit, means for transmitting signaling current to said line to operate said lamps and receivers at said 20 telephones as visible and audible signals respectively, means for removing said neon lamp at the desired telephone from said signaling circuit by shunting it with the telephone transmitter, said receiver being maintained in said circuit for talking purposes, the neon lamps of all other telephones preventing the passage of voice currents and the consequent loss in transmission from the called telephone.
25. In a telephone circuit, a telephone receiver 12. In a telephone circuit, a telephone receiver
- arranged to be operated both as a telephone instrument and as a signal, and a neon glow lamp connected in series with said receiver in the signaling circuit to prevent the operation of the instrument by talking current and to permit the 5 operation thereof by signaling current.
13. In a telephone circuit, a telephone receiver operated either as a signal or for telephone purposes, and a neon glow lamp connected to said receiver and operated therewith as a signal but 10 rendered inoperative when said receiver is used for telephone purposes.
14. In a telephone circuit, means for transmitting signaling current and talking current over said circuit, a telephone receiver in said circuit 15 responsive to said signaling current to operate as a call signal and responsive to said talking current to operate for talking purposes, and a neon glow lamp connected to said telephone receiver for permitting said signaling current but not said 20 talking current to operate said receiver.
15. In a telephone circuit, means for transmitting signaling current and talking current over said circuit, a telephone receiver in said circuit responsive to said signaling current to operate as 25 a call signal and responsive to said talking current to operate for talking purposes, a neon glow lamp connected to said telephone receiver for permitting said signaling current but not said 30 talking current to operate said receiver, and means for rendering said neon glow lamp inoperative and to change said circuit to permit the passage of said talking current.
